UNITED STATES PATENT OFFICE.

WILLIAM ERICKSON, OF SAN FRANCISCO, CALIFORNIA, ASSIGNOR OF ONE-FOURTH TO
HALFDAN C. THOMSEN, OF SAN FRANCISCO, CALIFORNIA.

CALKING DEVICE.

1,118,543.

Specification of Letters Patent. Patented Nov. 24, 1914.

Application filed November 19, 1913. Serial No. 801,991.

To all whom it may concern:

Be it known that I, WILLIAM ERICKSON, residing in the city and county of San Francisco, State of California, have invented certain new and useful Improvements in Calking Devices, whereof the following is a specification.

This invention relates more particularly to a pneumatic hand holding calking tool and consists in general terms in a guide to which the oakum is fed and through which it is driven by the calking irons into the seam to be calked. The guide is provided with a device for directing the oakum and leading the calking iron against it, and for raising the iron free from the oakum on its return stroke.

The apparatus also includes means by which the stroke of the iron or its penetration into the seam may be controlled. This feature and others which enter into the invention will be fully set forth in the subjoined description and more particularly defined in the claims at the end hereof.

25 In the accompanying two sheets of drawings I have illustrated an apparatus containing my invention in its best form.

In these drawings: Figure 1 is a plan view of my invention showing the end of the pneumatic cylinder with the calking iron; the guide portion of the latter being broken away to more perfectly illustrate the interior construction. Fig. 2, is a side view of the same with the oakum guide in section and also the attaching rings by which it is connected to the cylinder. Fig. 3, is a side elevation of the apparatus. Fig. 4, is a longitudinal section of the automatic cylinder showing the piston and the calking iron in elevation. Fig. 5, is a perspective view showing the end of the cylinder and the calking iron and oakum guide and connections. In this figure a modified form of spring is shown for causing the calking iron to engage the oakum after the return stroke and at the beginning of its forward stroke. Fig. 6, is a sectional elevation of the same; and Fig. 7, is a front end elevation.

50 In these figures 1 represents the pneumatic cylinder;—2 is the piston reciprocating therein and 3 is the calking iron operated thereby and serving to drive the oakum into the seam to be calked.

At the end of the cylinder 1, attached 55 thereto by rings 4 and 5 and side arms 6 is

a shield and oakum guide 7, through which the oakum 8 is fed. The shield 7 is pivoted at 9 to the ends of the side arms 6, so as to be capable of limited oscillation thereon, said oscillation being at right angles to the seam to be calked. 60

At 10 is a finger, one on each side of the oakum guide pivoted at 11 and extending forward toward the seam. The oakum 8 is fed in at the rear of the guide along the 65 calking iron 3, as clearly shown in Fig. 2. The iron 3, being driven forward by the pneumatic cylinder engages the oakum below the pivot 11, and drives it under the fingers 10 into the seam. In doing this the 70 calking iron 3 passes under the fingers 10 raising their free ends which drop again when the widest portion of the iron has passed them. On the return stroke the iron then rides up over the fingers, which free 75 it from the oakum until it is retracted back of the pivotal pin 11 when it drops down from the fingers against the oakum and is ready for a new forward stroke. To insure this drop of the iron upon the oakum 80 the spring 12 is provided which tilts up the back end of the shield as seen in Figs. 2 and 3.

The fingers 10 may be provided with springs (not shown) to depress their free 85 ends.

If desired a spring 13 shown in Fig. 5, may be applied to the calking iron 3 and depress its edge, the iron being pivoted at 14 for the purpose. It is immaterial 90 which of these two means is employed as the movement necessary is a relative movement of the iron 3 and the shield 7.

15 is a pilot wheel which may run along the seam to be calked and guide the hood 95 and together with the flange 16 hold it accurately in position.

The ring or collar 5 is provided with an oblique slot 17 which is engaged by pin 18 upon the end of the cylinder 1. The purpose of this construction is as follows: The operator holding the cylinder in one hand and the shield guide and its connections in the other, by a slight twisting movement can cause the cylinder and calking iron 3 to 100 advance or recede relatively to the shield 7, and thereby drive the tool deeper or less 105 deep into the seam.

Instead of fingers 10 above described I 110 may use springs 19 shown in Figs. 5, 6 and

7 which are preferably secured at their rear ends to the walls 20 of the shield 7, so that their forward ends will be free to spring back after the widest portion of the iron has passed that point.

21 is a guard plate covering the top front part of the shield guide 7 to prevent any accident to the fingers of the operator which may otherwise occur while operating the iron 3.

Having thus described my invention and believing I have produced useful and novel improvements in the art to which it appertains, let it be understood that I do not wish 15 to be limited to the exact arrangement of the several parts composing the same as many changes can be made without departing from the spirit thereof, but—

What I claim and desire to secure by 20 United States Letters Patent is:

1. In a pneumatic hand calking tool, in combination with the iron, a guide for directing the oakum toward the seam and means for holding said guide in position and cause the iron to engage said oakum.

2. In a pneumatic hand calking tool, in combination with the iron, an automatic adjustable guide for directing the oakum into the seam and holding it in position to be engaged by the iron and means for moving the iron laterally away from the oakum on its return stroke.

3. In a pneumatic hand calking tool, in combination with the iron, a cylinder therefor, a guide for directing the oakum to the seam, bars projecting from said cylinder for holding said guide in position and a pilot wheel connected to said bars for guiding said guide along the seam.

4. In a pneumatic calking tool, in combination with the iron, a guide for directing the oakum to the seam and fingers pivoted at their rear ends and having their forward ends depressed, the calking iron passing 45 under said fingers on its driving stroke and over them on its return stroke.

5. In a pneumatic calking tool in combination with the iron, a cylinder therefor, a guide for the oakum and means for 50 changing the projection of said guide from the cylinder whereby the depth of the driving is gaged.

6. In a pneumatic calking tool, in combination with the iron, a cylinder therefor, a guide for oakum mounted upon bars extending from the cylinder, collars supporting said bars upon the cylinder, one of said collars having an oblique slot, and a pin upon the cylinder engaging said slot.

7. In a pneumatic calking tool, in combination with the iron, a guide for directing the oakum to the seam, a device for holding the iron against the oakum on its driving

stroke and a spring for determining the relative position of the iron and the guide. 65

8. In a pneumatic calking tool, in combination with the iron, a guide for directing the oakum into the seam and holding it in position to be engaged by the iron and springs adapted to cause a relative lateral displacement of the iron and the oakum on the return stroke of the former. 70

9. A seam calking tool comprising a shield for holding the material to be driven into the seam, an iron for driving said material, a guard plate above said iron and means for operating said iron between said shield and said guard plate. 75

10. A seam calking tool comprising a spring actuated shield for holding the material to be driven into the seam, an iron for driving said material, means for operating said iron and means for regulating its driving depth. 80

11. A seam calking tool comprising a shield for holding and guiding the material to be driven into the seam, a guard plate for covering said shield and an iron operating between said shield and guard plate for driving said material. 85

12. A seam calking tool comprising a spring actuated shield for guiding the material to be driven into the seam, an iron for driving said material and means for causing said iron to engage said material upon said shield. 90

13. A seam calking tool comprising a pivoted guiding shield for the material to be driven into the seam, an iron for driving said material and spring means for causing 100 said iron to engage said material.

14. A seam calking tool comprising a pivoted guiding shield for the material to be driven into the seam, an iron for driving said material and means for changing the position of said guiding shield and causing said iron to engage said material upon said shield. 105

15. A seam calking tool comprising a pivoted tilting guiding shield for the material to be driven into the seam, an iron for driving said material and spring means for causing 110 said shield to tilt.

16. A seam calking tool comprising a guiding shield for directing the material to be driven into the seam, and a pivoted iron adapted to engage said material upon said shield and drive the same into the seam. 115

In testimony that I claim the foregoing I have hereto set my hand in the presence of 120 witnesses, this 1st day of Nov. 1913.

WILLIAM ERICKSON.
